UNITED STATES PATENT OFFICE.

BERNARD F. WEBER, OF CHICAGO, ILLINOIS.

BUILDING BRICK.

1,425,302.

Specification of Letters Patent. Patented Aug. 8, 1922.

Application filed June 23, 1919, Serial No. 306,086. Renewed May 29, 1922. Serial No. 564,622.

To all whom it may concern:

Be it known that I, BERNARD F. WEBER, a citizen of the United States, residing at Chicago, in the county of Cook and State of Illinois, have invented a certain new and useful Improvement in Building Bricks, of which the following is a full, clear, concise, and exact description, reference being had to the accompanying drawings, forming a part of this specification.

My invention relates to building bricks. More specifically, my invention embodies a novel method of constructing building walls and the like, characterized by the use of relatively large, hollow bricks. P
reminent advantages are gained by this method. By making the bricks of hollow formation, they can be made considerably larger than the ordinary solid bricks without involving excessive weight or reducing the facility with which they can be handled. The larger volume of the hollow bricks enables the brick layer to lay a given area of wall much more rapidly than with the smaller size solid brick. The rapidity with which a brick structure can be erected, and the labor expense involved, are potent factors in the competitive uses of brick and concrete.

Another advantage resides in the reduced weight of the wall structure as a whole, when constructed of these enlarged hollow bricks.

Other advantages are; the imperviousness of the wall to moisture and temperature due to the bodies of air entrapped in the hollow bricks; the reduced expense of freighting and handling the hollow bricks; and the saving in fuel and time in burning and drying the hollow bricks.

I am aware that the idea of building with large hollow bricks has been heretofore proposed, but these attempts have been for the most part limited to the foundations of buildings, low wall construction, and the attempts at combining clay bricks of ordinary standard type with a hollow brick have not been entirely successful in large wall areas; due to inability to bond a wall structure embodying two kinds of bricks, and to the difficulty of finishing the ends, corners, door

or window openings and similar situations where header bricks are required.

I have overcome these objections by the provision of a system of hollow bricks, which are formed to have novel co-operation to the end of adapting the bricks to any situation or wall structure capable of being erected with the ordinary solid type of bricks. This system comprises two brick units—a hollow stretcher brick and a hollow header brick. Both brick units have their hollow cavities arranged in such a manner as to entirely seal the air spaces in the completed wall. The wall or other structure is built up mainly with the hollow stretcher type of brick, the hollow header type of brick being employed for bonding the structure, closing the corners, etc.

In the accompanying drawing I have illustrated a preferred embodiment of my invention for explicitly illustrating the practice thereof.

Figure 1 is a fragmentary isometric view of a wall erected from my improved system of bricks;

Figure 2 is an enlarged isometric view of my improved hollow stretcher brick; and Figure 3 is a similar view of my improved hollow header brick.

Pursuant to the primary object of my invention I construct the stretcher brick 4 and the header brick 5 considerably larger than the ordinary solid bricks, preferably the size of two ordinary bricks, viz: 8" x 5" x 3 $\frac{1}{2}$ ". It is, of course, within the purview of my invention to construct these bricks the size of several ordinary bricks if desired, but I find that when constructed this large they become cumbersome and are difficult to handle with the dexterity required for rapid laying.

The bricks are preferably—though not necessarily—composed of clay, fired as in ordinary brick practice, and I intend the appended claims to include cement, or any other suitable material.

The stretcher brick 4 is formed with two rectangular air channels 6 extending longitudinally through the length of the brick and separated by a vertical web 7. It will be apparent that in each tier of bricks, the

webs 7 will be vertically aligned throughout the entire tier, thereby forming a practically continuous supporting column extending down through the series of bricks.

- 5 The header brick 5 is formed with the four rectangular air channels 8 extending downward through the vertical dimension of the brick, which corresponds to the 5" dimension as above outlined. These channels 10 are separated by the longitudinal and transverse webs 9 and 10. It will be noted that in the header type of brick the walls of the air channels bear practically no bending strain, and in the stretcher type of bricks 15 the bending strain is very slight for the reason that the channels have a very short horizontal span.

In Figure 1 I have shown an exemplary wall construction for the sake of explicitly 20 illustrating the cooperative relation between the two types of bricks, it being understood that the two types of bricks are capable of varied relation in different brick structures other than that herein shown. The wall 25 structure is built up primarily of courses of stretcher bricks 4 which are laid in parallel tiers with the joints lapping as in customary practice. The courses and tiers are cemented together by the mortar or other cement 30 indicated at 12. The stretcher bricks 4 are laid horizontally, end to end, with the air channels 6 co-extensive and forming long horizontal air chambers in the walls of the building. From the fact that these air 35 chambers lie horizontal, practically no thermal circulation is created and consequently these air chambers constitute very effective heat insulating means. The stretcher bricks 4 are laid on the narrow faces with the 37" 40 dimension lying horizontal to the tier so that the two tiers, together with the intervening layer of mortar 12 form a wall of substantially 8" thickness, or the length of one of the header bricks 5.

45 The bonding of the wall is accomplished by the use of the header bricks 5, which may be arranged in any preferred style or pattern of bond. In Figure 1, I have shown what is termed a "full header common bond" 50 consisting of a course of full headers 5 for every six or seven courses of stretchers 4. These header bricks are laid transversely to the courses of stretcher bricks and are preferably spaced so as to place a header 55 brick exactly over the joint of the two stretcher bricks below. The header bricks 5 are also laid on their narrow faces with the air channels 8 extending vertically, these air channels being, of course, blocked by the 60 courses of stretcher bricks above and below and consequently the vertical circulation is negligible.

The above described type of bond is one 65 of the most prevalent in ordinary laying practice, and has a particular advantage

with the present type of hollow bricks. This advantage follows from the fact that in this pattern of bond the bonding is accomplished by the continuous use of but one type of brick and hence no time is lost in selecting 70 the bricks. It will be apparent, however, that the header bricks 5 are capable of bonding a wall structure according to any preferred bonding pattern if desired.

Corners, and other angular formations 75 may be finished by the use of the header bricks 5, which are so arranged with respect to the body of the wall as to effectually close the ends of the air channels in the stretcher courses and present a smooth exterior surface. In closing the corner of two intersecting walls, such as shown in Figure 1, the closer brick at the end of each stretcher course on the outer face tier is substituted by a hollow header brick 5. The stretcher 80 courses usually overlap at the corner of the wall and consequently the series of header bricks 5 overlap at their ends in the form of a single tier of angularly disposed overlapping headers. It will be apparent that 90 these header bricks effectually seal the ends of the air chambers in the stretcher courses and present a smooth exterior surface.

In situations where smaller bricks are required, such as to fill in around a window 95 frame 14, it is entirely practicable to use ordinary solid bricks 15, as illustrated to the left in Figure 1. As I have previously remarked, the hollow bricks 4 and 5 are substantially twice as high as an ordinary solid 100 brick and consequently the two types of hollow and solid bricks have a desirable interchangeable relation.

In the appended claims wherein I refer to "header" bricks it is to be understood that 105 I am not limiting this type of brick solely to the operations of bonding and closing corners, such as I have above described, but include by this descriptive term all uses where in an end or side of the brick is exposed, as 110 in ordinary solid brick practice.

I claim:

1. A composite wall or the like comprising courses of hollow stretcher bricks with corner hollow header bricks all substantially 115 the same size and binder courses of the hollow header bricks, each stretcher and header brick presenting four plane unbroken surfaces, each stretcher brick having a web extending longitudinally therethrough and 120 each header brick having two transverse webs extending from side to side.

2. A composite wall or the like comprising courses of hollow stretcher bricks with corner hollow header bricks all substantially 125 the same size and standard bricks for window or door supports and the like, binder courses of header bricks, each header and stretcher brick presenting four plane surfaces, each stretcher brick having an open- 130

ing extending longitudinally therethrough and each header brick having a transverse web extending from side to side.

3. A composite wall or the like comprising double courses of hollow stretcher bricks with double corner hollow header bricks and binder courses of header bricks, each header and stretcher brick being approximately the

same size and having four plane sides, each stretcher brick having a web extending longitudinally therethrough and each header brick having transverse webs extending from side to side. 10

In witness whereof I hereunto subscribe my name this 18th day of June, 1919.

BERNARD F. WEBER.
